ELECTRICAL COIL-WINDING MACHINE

John William Miller, London N. W. 9, England, assignor to Goodmans Industries Limited, Wembley, Middlesex, England, a British company

Application March 3, 1943, Serial No. 477,883
In Great Britain July 16, 1942

19 Claims. (Cl. 242—9)

1

This invention relates to machines for winding coils as are used in electrical instruments, more particularly those known as moving coils.

Electrical coils are usually wound by hand and it takes about three minutes to do this.

It is the object of the present invention to provide a machine whereby single or multiple layer electrical coils can be wound automatically.

A further object of the invention is to provide means for ensuring that the separate turns of the coil are applied in abutting relationship.

Another object of the invention is to provide means for supplying wire to a former at an angle of lag which remains substantially constant until the wire has been wound the full length of the former.

Still another object of the invention is to provide means whereby in the case of multi-layer coils the wire is supplied to a former at an angle of lag, which is substantially constant in the separate layers but in opposite direction for each successive layer.

A still further object of the invention is to provide means for varying the direction of the angle of lag of the wire automatically as the end of each separate layer is reached.

Yet another object of the invention is to provide means whereby a wire guide receives an accelerated movement in the same direction at the end of a layer of turns so as to start its return movement with the same angle of lag but in the opposite direction.

A further object of the invention is to provide a machine which avoids the necessity of stopping the machine at the end of winding each separate layer for the purpose of coating the wound layer, before applying the next layer, with a suitable adhesive or insulating medium, by coating the wire with a suitable adhesive or insulating medium in liquid form before it is fed to a former.

These and other objects will appear from the following description, with reference to the accompanying drawings which show a preferred embodiment of the invention as applied to a coil winding machine.

In these drawings:

Fig. 1 shows an elevation.

Fig. 2 is a plan view, partly in section.

Fig. 3 is a section on the line III—III of Fig. 2.

Fig. 4 is an elevation partly in section looking at the left-hand side of Fig. 2, and

Fig. 5 shows a detail.

As shown in the drawings, the machine is provided with a supporting structure 1 of substantially inverted U-shape. In the structure is ro-

2

tatably mounted a shaft 2, 3 on which are located two collars 4, 5 of which one 5 is secured to the shaft, whilst the other 4 is loosely mounted on the shaft. The collars 4, 5 are connected together by a coiled spring 6. The purpose of this arrangement will be described hereinafter.

One the end of the shaft portion 2 is keyed a clutch member 7 provided with a conical surface.

On this end of the shaft portion 2 is slidably mounted a bush 9 on which is keyed a driving pulley 10 provided in the portion thereof adjacent the clutch member 7 with a groove 11 into which is fitted a ring 12 of leather or other friction material.

In order to hold the ring 12 in frictional engagement with the cam 8 for the purpose of driving the shaft 2, 3, the bush 9 is pressed towards the clutch member 7 by a spring 13 secured to a shaft 14, rotatably mounted in the structure 1, and carrying at its other end an operating lever 15.

In order to ensure engagement between the spring 13 and the bush 9 the latter is preferably provided with a conical end 16.

On the shaft portion 3 is keyed a pinion 17 which gears with a spur wheel 18 keyed to a shaft 19 rotatably mounted in the structure 1. The gear ratio between the pinion 17 and spur wheel 18 is preferably 1:2.

To the shaft 19 is keyed a worm 20 gearing with a worm wheel 21 secured to sleeve 22 rotatably mounted in a boss 23 depending from the top of the structure 1.

In the sleeve 22 is rotatably mounted a spindle 24 to the lower end of which is keyed a heart shaped cam 25, of a resilient nature, which carries a tooth 26 which co-operates with radial recesses provided over the entire adjacent face of the wormwheel 21. The free lower end of the spindle 24 is hardened and co-operates with a cam 27 in which is mounted a spring actuated ball which is opposite the end of the spindle 24 in the operative position of the machine.

To the upper end of the spindle 24 is keyed a cam cage 28 for the reception of one or more cams 29. The cams 29 are secured in position by a plate 30 secured to a boss of the cam cage 28 by screws 31.

The cams 29 are provided with cam grooves 32, 33.

With the grooves 32, 33 co-operates a pin 35 secured to a slide 36 slidably mounted on a lever 37 by pin and slot connections 38.

The slide 36 is provided with a second pin 39 adapted to co-operate with a stop lever 40 keyed

to a spindle 41 rotatably mounted in the structure 1. The end of the slide, at which the pin 35, is secured thereto, is connected by a link 75 to the lever 37.

The lever 37 is keyed to a spindle 42 mounted in a boss 43, secured to the structure 1, and provided with an arm 44 having a pointed end 45 co-operating with the pointed end 46 of a spring actuated plunger 47 in a housing 48 secured to the structure 1.

To the lower end of the spindle 42 is keyed a lever 49 connected by a spring 51 to a lever 52 secured to a container 53 containing a liquid adhesive or insulating material.

Between the levers 49, 52 is located a plate 53' provided with rounded ends for engaging with the levers 49, 52. The plate 53' is carried by a rod 54, passing therethrough, secured to a member 55 carried by a spindle 58 pivotally mounted in a bracket 56 secured to the structure 1.

The container 53 is mounted on a spindle 57 rotatably mounted in the bracket 56. The container 53 is closed by a cover 59 provided with a hole 60 through which wire, from a supply spool (not shown) is fed into the container 53.

In the container 53 is rotatably mounted a grooved guide roller 61, immersed in the liquid in the container 53, which serves to guide the wire through the liquid.

Near its upper end the container 53 is provided with a conical spout 62 having a longitudinal groove 63 in its upper surface along which the wire is passed. After the wire has been placed into the groove it is retained in the latter by a conical cap 64. The cap 64 is preferably provided with a longitudinal slit adapted to be brought into register with the groove when the wire is to be placed into the groove 63 so that the wire can be placed into the recess 63 without removing the cap 64, whereupon the cap 64 is turned to bring the slit and groove out of register whereby the wire is retained in the groove 63.

The wire from the spout 62 is secured to a pin 65a carried by a chuck 65 mounted on the shaft portion 3. The chuck 65 receives a former 65b on which the wire is to be wound.

To the lower end of the spindle 41 is keyed a lever 66 connected by a spring 67 to a pawl lever 68 keyed to the shaft 14. The lever 68 co-operates with a projection 69 on the collar 4. On the shaft 14 is also keyed a lever 70 of which the free end engages with a notch in the lever 66 when the various parts are in the position shown in the drawings.

To the spindle 41 is secured a sleeve 71 around which is coiled a spring 72 of which one end is secured to the sleeve whilst its other end is attached to a lever 73. The lever 73 is loosely mounted at one end on the spindle 41, whilst its other end bears against the heart cam 25 by means of a roller 75 (Fig. 5).

A return spring 74 is connected at one end to the structure 1 and at the other end to the lever 15.

The operation of the machine above described is as follows:

The various parts are in the position as shown in the drawing and it is to be assumed that a former has been fitted in the chuck 65 and a wire to be coated and wound on the former has been passed through the hole 60, around the roller 61, along the groove 63 in the spout and the end attached to the chuck.

The lever 15 is depressed thus turning the 75

shaft 14. As a result of turning the shaft 14 the spring 13 is brought into engagement with the conical end 16 of the bush 9 so that the friction lining 11 is pressed against the conical surface 8 of the clutch member 7 whereby the shaft 2, 3 is driven by the pulley 10. It may here be mentioned that a driving belt for engagement with the pulley 10 is preferably offset so as to assist in keeping the friction lining 11 in contact with the conical surface 8.

The turning of the shaft 14 also disengages the pawl lever 68 from the projection 69, whilst the lever 70 is engaged with the lever 66 which as a result of the action of the spring 67, moves the lever 40 in a clockwise direction (Fig. 2) until it meets the pin 39.

As a result of the turning of the shaft 14 the cam 27 raises the spindle 24 as a result of which the tooth 26 is brought into engagement with one of the radial recesses in the worm wheel 21 thus coupling the spindle 24 to the worm wheel 21. The raising of the spindle 24 also brings the cam carrier 28 into such a position that the pin 35 is opposite the cam groove 32 of one of the cams 29.

As the shaft 2, 3 is now being driven by the pulley 10, the chuck 65 with the former is rotated and the wire, having been secured so that it is lying in the corner formed by the cheek of the chuck and the former, now takes up a position closely adjacent to the cheek until one revolution has occurred when the wire will follow the guide formed by the wall of the preceding turn of wire.

The spout 62 is so positioned relatively to the former that the wire feed point to the former lags behind the turns of wire as they are wound on the former.

During the winding operation the pin 35 follows the cam groove 32, which is a true spiral, as a result of which the lever 37 turns about the axis of its spindle 42 in an anti-clockwise direction. As the lever 49 is keyed to the spindle 42 it causes the lever 52 to follow its movement through the spring 51 thus turning the spout 62 about the axis of the spindle 57 on which the container 53 is mounted.

The ratio of the levers 37, 49 and 52 and spout 62 are such that when the pin 35 has moved from one of the cam grooves 32 to the other, the spout 62 has traversed the length of the former on which the wire is to be coiled. The spout 62 thus moves substantially in synchronism with the winding of the wire on the former.

Whilst this movement of the spout 62 is taking place, the end 45 of the lever 44 is forcing the spring-actuated plunger 47, which is now tensioning the lever 37 in a clockwise direction, into its housing 48 until, when the pin 35 reaches the central point of travel of the cam groove 32, the end 45 passes over the pointed end 46, thus transferring the tension imparted to lever 37 from a clockwise to an anti-clockwise direction. When the pin 35 reaches the end of the cam groove 32, it is sprung by the action of the spring plunger 47 in contact with lever 44 in an anti-clockwise direction until brought up against the contour of the cam which follows, thus rapidly reversing the angle of the spout to the correct position for the winding of the second layer in the reverse direction, this movement being synchronised with the approach of the last turn of the first layer against the cheek at the finishing end of the first layer.

Immediately the last turn is wound the wall

of the cheek of the chuck will prevent the continuance of the first layer so that the turn immediately following will be forced to lift itself on to the end of the first layer, so forming the first turn of the second layer. The cam groove 33 now guides the pin, but in an opposite direction when the same cycle of movements are brought into operation with reversal at the end of each layer until the four layers are completed.

At the end of the cam groove 33 is provided a pin 78 which is reached by the pin 35 when the final layer of wire on the former has been completed. When the pin 35 reaches the pin 78, this pin, as it turns with the cam carrier 26, moves with it the pin 35 and thus the slide 36 to which the latter is secured.

The pin 39 on the slide 36 thus moves the stop lever 40 in an anti-clockwise direction as a result of which the lever 63 is rocked into the path of the projection 69 through the medium of the lever 66 and the spring 67. As a result the shaft 14 is rocked in a clockwise direction thus disengaging the spring 13 from the end of the bush 9 and relieving the pressure between the friction lining 11 and the clutch member 10, raising the lever 15 and, as a result of a rotation of the cam 27, allowing the spindle 24 with the cam carrier 28 to drop. During this movement the end 45 has snapped over the spring plunger 47 and the lever 73, through its roller 75 acting on the heart cam 25 has brought the cam carrier 28 into its starting position.

All the parts are now in their starting position.

The wound former is now removed and a fresh former is placed in position for winding.

The operations above described are now repeated for winding wire on the fresh former.

The spring 6 between the two collars 4, 5 serves to take up the shock of the engagement of the lever 63 with the projection 69 and to absorb the energy that is still stored in the shaft 2, 3 thus preventing damage to wound coil.

Whilst the machine has been described above for winding four-layer coils it will be understood that it may be used for winding any number of layers including a single layer coil, according to the number of cams employed. The actual following movement of the feed point may be intermittent instead of regular and in cases where a small number of turns per layer are being wound, it may not be necessary to make use of a following movement, relying upon the sudden movement of the feed point from side to side at the end of each layer to produce the conditions for the winding of the coil in the manner described.

It will be understood from the foregoing that the wire is always fed to the former from a point which lags in relation to the point of contact of the wire with the former, so that the angle of feed is maintained substantially constant as the winding of the layer proceeds by causing the spout 62 to turn about the axis of the spindle 57. In this manner the separate turns of wire are wound closely side by side. This result is ensured as the separate layers are formed by imparting an accelerated movement to the spout 62 in its direction of movement as the end of one layer is reached and before the winding of the next layer commences which is started with the same angle of lag as the previous layer but in the opposite direction.

In order to allow for minute variations or discrepancies in the diameter of the wire which would vary the number of turns for a predeter-

mined length of coil the space between the cams can be varied so that the accelerated movement is arranged to coincide with the winding of the final turn of each layer.

In order to limit the amount of adhesive still adhering to the wire as it leaves the groove 63 in the spout, the groove 63 is opened out at the end nearest to the cement container to allow a piece of felt or other absorbent material to be fitted flush with the conical surface of the spout 62 so that the wire will pass between the spout cap and the felt thereby limiting the amount of cement adhering to the wire on its passage through the groove 63.

I claim:

1. In a coil winding machine the combination of a rotatably mounted former on which wire is adapted to be coiled, means for rotating said former, a guide for guiding wire onto said former, said guide being mounted for oscillation about an axis transverse to the axis of the former, so that the guide, during oscillation, will move in a direction generally longitudinally of the former, and means for oscillating said guide relative to the former until the required number of turns has been wound onto the former, the initial position of the guide to the former and the rate of oscillation thereof relative to the rotative speed of the former being such that the guide maintains a substantially constant angle of lag relative to turns of wire wound onto the former until the required number of turns has been wound thereon.

2. In a coil winding machine the combination of a rotatably mounted former on which wire is adapted to be coiled, means for rotating said former, a guide for guiding wire onto said former, said guide being mounted for oscillation about an axis transverse to the axis of the former, so that the guide, during oscillation, will move in a direction generally longitudinally of the former, and means for oscillating said guide relative to the former until the required number of turns has been wound onto the former, the initial position of the guide to the former and the rate of oscillation thereof relative to the rotative speed of the former being such that the guide maintains a substantially constant angle of lag relative to turns of wire wound onto the former until the required number of turns has been wound thereon, the means for oscillating the guide being constructed and arranged to move it through a distance in excess of the distance between the start and finish of wire turns on the former, and means operative when the wire guide reaches the end of its oscillatory movement in one direction for oscillating it in the opposite direction to wind another layer of turns of wire onto those already on the former and causing the guide to assume the same angle of lag which it maintained while the previous layer of turns was being wound, but in the opposite direction.

3. In a coil winding machine according to claim 2, wherein means are provided for oscillating said guide at a substantially uniform rate during the application of the separate turns of wire to the former, and wherein means are provided for imparting an accelerated movement to said guide at the end of each layer of turns of wire so as that said guide starts its return movement with the same angle of lag for the second layer of wire turns but in the opposite direction to the lag for the first layer of wire turns.

4. In a machine according to claim 2, a spindle 75 mounted for oscillatory movement, means con-

necting said spindle with the wire guide, whereby oscillation of the spindle causes oscillation of the guide, a lever connected to said spindle for oscillation therewith, cam means, and means connecting said lever with the cam means whereby relative movement by the cam means and the lever causes oscillatory movement to be imparted to the lever and spindle and the wire guide oscillated.

5. In a machine according to claim 2, a spindle mounted for oscillatory movement, means connecting said spindle with the wire guide, whereby oscillation of the spindle causes oscillation of the guide, a lever connected to said spindle for oscillation therewith, cam means, and means connecting said lever with the cam means whereby relative movement by the cam means and the lever causes oscillatory movement to be imparted to the lever and spindle and the wire guide oscillated, a second lever mounted on said spindle for oscillation therewith and means for applying a spring bias to said second lever to cause a resistance to movement to be imparted to said first lever and said spindle.

6. In a machine according to claim 2, a spindle mounted for oscillatory movement, means connecting said spindle with the wire guide, whereby oscillation of the spindle causes oscillation of the guide, a lever connected to said spindle for oscillation therewith, cam means, and means connecting said lever with the cam means whereby relative movement by the cam means and the lever causes oscillatory movement to be imparted to the lever and spindle and the wire guide oscillated, a container for coating material, and means for applying material from said container to wire passing to said wire guide, whereby the wire wound on said former will have a coating of said material thereon.

7. In a machine according to claim 2, a spindle mounted for oscillatory movement, a lever keyed to said spindle, a tension spring between said lever and a part of the operating means for the wire guide, a pivotally mounted arm, a plate carried by said arm and interposed between said lever and said part of the operating means for the wire guide, a second lever keyed to said spindle, a pin carried by said second lever, and cam means with which said pin cooperates to control the oscillation of the wire guide.

8. In a machine according to claim 1, wherein said guide comprises a conical spout, said spout being provided in its periphery with a longitudinal groove extending along the entire length of said spout, and a conical cap rotatably fitted on said spout, said cap being of corresponding shape to said spout, said cap having a longitudinal slit therein, the arrangement being such that for inserting the wire into the said groove the said slit is brought into register with said groove, whereupon the slit is moved out of register with the groove so that the cap prevents the wire leaving the groove.

9. In a machine according to claim 2, a rotatable spindle, a lever mounted on said spindle for movement therewith, means so connecting said lever to said guide that movement of the lever imparts movement to the guide, a second lever keyed to said spindle, a pin secured to said second lever, a cam device with which said pin cooperates, a stop pin carried by said cam device, said stop pin being located in a position corresponding with the last turn of wire to be wound on the former, said stop pin being adapted to cooperate with the pin carried by said second lever,

and return mechanism for resetting said guide and said cam device in their starting positions, said return mechanism co-operating with said pin.

5. 10. In a machine according to claim 2, a rotatable spindle, a lever mounted on said spindle for movement therewith, means so connecting said lever to said guide that movement of the lever imparts movement to the guide, a second lever keyed to said spindle, a pin secured to said second lever, a cam device with which said pin co-operates, a stop pin carried by said cam device, said stop pin being located in a position corresponding with the last turn of wire to be wound on said former, said stop pin being adapted to co-operate with the pin carried by said second lever, a second pin secured to said second lever, a rocking lever co-operating with said second pin, and mechanism for returning the mounting means for the former to its starting position, said return mechanism being associated with said rocking lever.

11. In a machine according to claim 2, including a driving shaft, a driving pulley mounted freely on said shaft, a friction clutch including two clutch elements, one of said clutch elements being secured to said driving pulley and the second of said clutch elements being keyed to said driving shaft, a pair of collars on said driving shaft, one of said collars being keyed to said driving shaft, whilst the second of said collars is loose on said driving shaft, a coiled spring lapped around said collars, one end of said coiled spring being secured to one of said collars and the other end of said coiled spring being secured to the second of said collars, a projection on said loose collar, a rocking lever adapted to co-operate with said projection, means for holding said rocking lever out of the path of said projection during the wire winding operation, and means for moving said rocking lever into the path of said projection when the wire winding operation has been completed.

12. In a machine according to claim 2, a rotatable spindle, a lever mounted on said spindle for movement therewith, means so connecting said lever to said guide that movement of the lever imparts movement to the guide, a second lever keyed to said spindle, a pin secured to said second lever, a cam device with which said pin co-operates, said cam device including a cam carrier, a spindle on said cam carrier, a shaft, a cam on said shaft, a spring actuated member in said cam, said cam being adapted to co-operate with said cam carrier spindle, a rocking lever keyed to said shaft, and means for actuating said rocking lever, the arrangement being such that during the wire winding operation the rocking lever is in a position in which the cam holds the cam carrier in a raised operative position, whilst when the wire winding operation has been completed the rocking lever is moved into a position so that the cam allows the cam carrier to drop into the inoperative position under the action of gravity.

13. In a machine according to claim 2, the combination comprising a driving shaft, a chuck mounted on said driving shaft, the former being mounted on said chuck, a secondary shaft, a gearing between said driving shaft and said secondary shaft whereby said secondary shaft is driven in the opposite direction to said driving shaft, a worm on said secondary shaft, a cam device operatively connected to said guide, a

spindle connected to said cam device, a worm wheel loosely mounted on said spindle, said worm wheel having radial recesses in one face thereof, and a tooth secured resiliently to said spindle, said tooth co-operating with said recesses.

14. In a machine according to claim 2, including a driving shaft, a driving pulley mounted freely on said shaft, a friction clutch including two clutch elements, one of said clutch elements being secured to said driving pulley and the second of said clutch elements being keyed to said driving shaft, a pair of collars on said driving shaft, one of said collars being keyed to said driving shaft, whilst the second of said collars is loose on said driving shaft, a coiled spring lapped around said collars, one end of said coiled spring being secured to one of said collars and the other end of said coiled spring being secured to the second of said collars, a projection on said loose collar, a rocking shaft, an operating lever on said shaft, a spring on said shaft, said spring being adapted to hold said clutch in its engaging position, a rocking lever keyed to said shaft, said operating lever when moved into an operative position serving to move said rocking lever out of the path of said projection and to move said spring into clutch engaging position, means for holding said rocking lever out of the path of said projection and means for releasing said rocking lever.

15. In a machine according to claim 2, including a driving shaft, a driving pulley mounted freely on said shaft, a friction clutch including two clutch elements, one of said clutch elements being secured to said driving pulley and the second of said clutch elements being keyed to said driving shaft, a pair of collars on said driving shaft, one of said collars being keyed to said driving shaft, whilst the second of said collars is loose on said driving shaft, a coiled spring lapped around said collars, one end of said coiled spring being secured to one of said collars and the other end of said coiled spring being secured to the second of said collars, a projection on said loose collar, a rocking shaft, an operating lever on said shaft, a spring on said shaft, said spring being adapted to hold said clutch in its engaging position, a rocking lever keyed to said shaft, said operating lever when moved into an operative position serving to move said rocking lever out of the path of said projection and to move said spring into clutch engaging position, means for holding said rocking lever out of the path of said projection, and means for releasing said rocking lever, said means for holding and releasing said rocking lever including a second lever keyed to said rocking shaft, a rotatable spindle, a spring operatively associated with said rotatable spindle, said spring normally tending to urge said rotatable spindle into its normal position, a third lever keyed to said rotatable spindle, said third lever being adapted to engage said second lever during operation of the machine so as to hold said rocking lever out of the path of said projection, a spring connected at its opposite ends to said rocking lever and to said third lever, a stop lever on said spindle, and means co-operating with said stop lever, the ar-

angement being such that when the stop lever is actuated at the end of a coil winding operation the third lever is disengaged from the second lever and the spring pulls the rocking lever into the path of said projection.

16. In a machine according to claim 2, the combination comprising a driving shaft, a chuck mounted on said driving shaft, the former being mounted on said chuck, a secondary shaft, gearing between said driving shaft and said secondary shaft whereby said secondary shaft is driven in the opposite direction to said driving shaft, a worm on said secondary shaft, a cam device operatively connected to said guide, a spindle connected to said cam device, a worm wheel loosely mounted on said spindle, said worm wheel having radial recesses in one face thereof, a resilient heart-shaped cam secured to said spindle, adjacent said worm wheel, a tooth secured to said heart-shaped cam adjacent the point thereof and on the face thereof adjacent the recesses in said worm wheel, said tooth being adapted to co-operate with said recesses, and a spring actuated lever co-operating with said heart-shaped cam, said spring actuated lever being adapted to return the heart-shaped cam, and thus the cam device, into its starting position after the coil winding operation has been completed.

30 17. In a machine according to claim 2, a rotatable spindle, a lever mounted on said spindle for movement therewith, means so connecting said lever to said guide that movement of the lever imparts movement to the guide, a second lever keyed to said spindle, a pin secured to said second lever, and a cam device with which said pin co-operates, said cam device including a plurality of cams which are relatively adjustable to allow for minute variations and discrepancies in wire diameter and for varying the number of turns of wire in each successive layer.

45 18. In a machine according to claim 2, a rotatable spindle by which said lever is carried, a rotatable spindle, a lever mounted on said spindle for movement therewith, means so connecting said lever to said guide that movement of the lever imparts movement to the guide, a second lever keyed to said spindle, a slide slidably mounted on said second lever, a pin on said slide, a cam device with which said pin co-operates, a stop pin in said cam device, said stop pin being adapted to co-operate with said pin at the end of the coil winding operation, a second pin secured to said slide, and a stop lever co-operating with said second pin.

60 19. In a machine according to claim 2, a spindle mounted for oscillatory movement, means connecting said spindle with the wire guide, whereby oscillation of the spindle causes oscillation of the guide, a lever connected to said spindle for oscillation therewith, a rotatable member having a cam groove therein, a pin carried by said lever and extending into said cam groove, whereby rotation of said rotatable member causes an oscillatory movement to be imparted to the lever and spindle and the wire guide oscillated.

JOHN WILLIAM MILLER.
